UNITED STATES PATENT OFFICE.

GUY BALDWIN, OF MARK CENTER, OHIO, ASSIGNOR OF ONE-HALF TO ARNOLD CLARK,
OF LATTY, OHIO.

DISK JOINTER.

1,163,200.

Specification of Letters Patent. Patented Dec. 7, 1915.

Application filed May 19, 1915. Serial No. 29,148.

To all whom it may concern:

Be it known that I, GUY BALDWIN, a citizen of the United States, residing at Mark Center, in the county of Defiance and State 5 of Ohio, have invented a new and useful Disk Jointer, of which the following is a specification.

The present invention appertains to disk jointers used for agricultural purposes, and 10 aims to provide a novel and improved jointer attachment for a plow beam or other suitable support.

It is the object of the invention to provide a disk jointer device of such construction, that the disk may be reversed and adjusted to most effectively serve its office under various conditions.

Another object of the invention is the provision of a novel means for mounting and 20 carrying the cutter disk whereby the same will be supported properly.

Another object of the invention is the provision of a unique means for scraping and cleaning the cutter disk, said means being 25 reversible in order that when the disk is adjusted to reversed positions, the scraping means may also be reversed to operate properly at either position of the disk.

It is also within the scope of the invention 30 to provide a disk jointer having the features above noted, and which at the same time, is comparatively simple, non-encumbering and inexpensive in construction, as well as being convenient, practical and efficient in use.

With the foregoing and other objects in 35 view which will appear as the description proceeds, the invention resides in the combination and arrangement of parts and in the details of construction hereinafter described 40 and claimed, it being understood that changes in the precise embodiment of the invention herein disclosed can be made within the scope of what is claimed without departing from the spirit of the invention.

45 The invention is illustrated in the accompanying drawing, wherein:

Figure 1 is a side view of the disk jointer. Fig. 2 is an opposite side view thereof. Fig. 3 is a top view of the device. Fig. 4 is a sectional detail on the line 4—4 of Fig. 3, this view being on a slightly enlarged scale.

Fig. 5 is an enlarged sectional detail taken on the line 5—5 of Fig. 3.

In carrying out the invention, there is provided a standard or hanger 1 whose upper 55 end portion is held by a clamp 2 applied to the beam B of a plow or other agricultural implement. This clamp 2 embodies a plate 3 resting against one side of the beam B and having bolts 4 engaged therethrough 60 above and below the beam, and a bar 5 is engaged to the bolts 4 and bears against that side of the beam B opposite the plate 3. Thus, when the bolts 4 are tightened, the clamp 2 will be securely held in position 65 upon the beam, it being noted that the clamp may be adjusted or reversed, as desired or necessary. The plate 3 has an upright sleeve 6 upon its outer side through which the upper end portion of the standard 1 is fitted 70 for rotary and sliding adjustments, whereby the standard may be rotated to various angular positions and may be adjusted vertically. Set screws 7 are carried by the sleeve 6 for engaging the standard 1 to clamp the stand- 75 ard at any adjusted position. The lower end portion of the standard is offset at one side, as at 8, the lower offset end portion 8 depending below the beam B. An upright sleeve 9 is slipped upwardly upon the end portion 8 of 80 the standard 1 and is adapted to be adjusted angularly around the end portion 8 of the standard, set screws 10 being carried by the sleeve 9 for engaging the standard 1 to clamp the sleeve 9 at any adjustable position. 85 The lower end portion of the sleeve 9 carries the cutter disk 11 which is of concavo-convexed formation, and which has its edge sharpened. The edge of the disk 11 may be serrated, if desired, for preventing the accumulation of trash in front of the disk during the use thereof. In order to carry the disk 11 for rotation by the lower end portion of the sleeve 9, the lower end portion of the sleeve is provided with a lateral socket 12 90 at one side, and a horizontal tubular bushing 13 has one end flanged, as at 14, and seated within the socket 12. The outturned annular flange 14 of the bushing 13 fits snugly within the socket 12, and the bushing 13 projects laterally from the lower end of the sleeve 9 to carry the disk 11. The flanged

end of the bushing 13 has one or more recesses 14 which receive one or more lugs 15 projecting from the sleeve 9 within the socket 12, whereby the bushing 13 is prevented from rotating. The disk 11 has a hub 16 attached to its central portion, and said hub is journaled upon the bushing 13. The end of the hub 16 adjacent the sleeve 9 is received by the socket 12 and bears against the flange 14 of the bushing. A cap 17 is fitted upon the outer end of the hub 16 and bears against the outer end of the bushing 13, and a bolt or clamping element 18 is engaged through the cap 17, bushing 13 and lower end portion of the sleeve 9. A collar 19 is secured upon the bolt 18 and bears against the cap 17 and a nut 20 is threaded upon the bolt 18 and bears against the sleeve 9 for clamping the bushing 13 tightly in place against the sleeve 9, whereby the disk 11 will be firmly supported for rotary movement. The hub 16 is journaled upon the bushing 13 between the flange 14 of the bushing 13 and the cap 17, and the disk may rotate freely and without objectionable vibration or play.

The bolt or rod 18 is utilized for carrying the scraping or cleaning means, and to this end, the bolt or rod 18 has an angularly extending arm or portion 21. The arm 21 carries the scraper 22, this scraper embodying a plate formed and bent to provide two wings 23 arranged at an obtuse angle relative to one another and having their remote edges shaped to conform to the concaved face of the disk 11. Strips 24 are secured to the back of the scraper 22 at the median portion thereof between the wings 23, and the strips 24 embrace the arm 21 and provide bearings for journaling or mounting the scraper for swinging movements upon the arm 21. The strips or bearings 24 are disposed at the ends of the scraper 22, and nuts 25 are threaded upon the arm 21 and bear against the strips or bearings 24 for clamping the scraper 22 at the position to which is set or swung. The wings or blades 23 of the scraper have tips 26 at those ends remote from the center of the disk 11 which project slightly beyond the periphery or margin of the disk and the tips 26 are curved away from the back of the wings 23 to assist in deflecting the dirt or soil to one side.

In use, by loosening the set screws 7, the standard 1 may be adjusted angularly and vertically with respect to the plow beam B for properly positioning the standard according to the circumstances, and by loosening the set screws 10, the sleeve 9 may be adjusted for properly positioning the disk 11 with respect to the standard. These adjustments enable the disk to be properly positioned upon either right or left hand plows, according to the circumstances.

The scraper 22 is properly adjusted in order that the proper wing or blade 23 will be disposed adjacent the concaved face of the disk 11 to coöperate therewith for scraping the dirt from said face of the disk. The arm 21 projects angularly forward and rearward, and is inclined, to hold the scraper 22 in a rearwardly inclined position, and the wing or blade 23 which co-operates with the disk will be inclined to one side, whereby the scraper will not only remove the dirt or soil from the disk, but will also assist in throwing or turning the soil to one side. The angular position of the arm 21 may be adjusted by loosening the nut 20 to allow the bolt or rod 18 to be turned. When the disk 11 is reversed, the scraper 22 may be readily reversed to bring the other wing or blade 23 into operation, and the arm 21 may be swung or adjusted properly, as will be apparent.

What is claimed is:

1. In a device of the character described, a supporting member, a cutter disk, the supporting member having a portion upon which said disk is journaled, a member engaged to said portion for rotary adjustment and having an angularly extending arm, and a reversible scraper mounted upon said arm for rotary adjustment and having opposite wings adapted to be brought into coöperation with the disk. 95

2. In a device of the character described, a supporting member, a cutter disk, the supporting member having a portion upon which said disk is journaled, a member engaged to said portion for rotary adjustment and having an angularly extending arm, a scraper having bearings journaled upon said arm and having opposite wings arranged to be swung into coöperation with the face of the disk, and means for clamping said bearings upon said arm for holding the scraper in position. 100 105

3. In a device of the character described, a supporting member, a cutter disk, the supporting member having a portion upon which the disk is journaled, an angularly extending arm adjustably engaged to said portion for attachment to various angles, and a scraper having opposite wings to be brought into coöperation with the face of the disk, the median portion of the scraper being carried by said arm for angular adjustment, said wings being arranged to be inclined outwardly away from the disk when the wings coöperate with the disk, and those ends of the wings remote from said portion being curved to assist in deflecting the soil to one side. 110 115 120 125

4. In a device of the character described, a supporting member, a bushing having one end resting thereagainst, a cutter disk having a hub journaled upon said bushing, a rod engaged through said bushing and sup- 130

porting member and having an angularly extending arm, said rod being adapted to be rotated when loosened, a nut threaded upon said rod for clamping the bushing to the 5 supporting member, and a reversible scraper adjustably mounted upon said arm for co-operation with the face of the disk.

In testimony that I claim the foregoing as my own, I have hereto affixed my signature in the presence of two witnesses.

GUY BALDWIN.
